X-RAY TUBE

Werner Ehrenberg, Hayes, and Walter Eric Spear,
London, EnglandApplication April 7, 1950, Serial No. 154,562
In Great Britain March 22, 1950

6 Claims. (Cl. 250—93)

1

This invention relates to X-ray tubes and has for its object to provide improved and simplified X-ray tubes in which the electrons from a thermionic cathode are concentrated in a fine focus on the anti-cathode.

For many purposes, notably for crystallographic work and micro-radiographic work generally, it is required to provide an X-ray tube in which the electrons from a thermionic cathode are focussed to a very small area on the anti-cathode. Hitherto great difficulties have been experienced in satisfying this requirement without excessive complexity in structure or inconvenience in operation and known X-ray tube arrangements capable of giving a fine electron beam focus on the anti-cathode have involved the use of magnetic focussing, or of complex electrode systems, or of an inconveniently large number of different, high, operating potentials applied to different electrodes. The present invention avoids these defects and provides improved X-ray tubes which will give a focus of less than one-tenth of a millimeter in diameter on the anti-cathode purely electrostatically i. e. without using magnetic focussing, without requiring a considerable number of high operating potentials and by means of an electrode system of unusual mechanical simplicity. Indeed, as will be seen later, in the preferred embodiments of the invention, the only electrode of the tube which is not at cathode potential, or in the region of cathode potential, is the anti-cathode itself.

According to this invention an X-ray tube comprises a cathode, an anti-cathode, and an electrostatic lens electrode system providing an equi-potential surface in the region of cathode potential said equi-potential surface substantially surrounding the electron discharge path from cathode to anti-cathode, extending at least over the whole length of said path and being of a diameter which is relatively small at the cathode end of said path and relatively large at the anti-cathode end thereof.

The electrostatic lens electrode system may be such as to produce an equipotential surface in the region of cathode potential and which increases gradually in diameter from the cathode end to the anti-cathode end of the electron discharge path. It is, however, preferred to increase the diameter of said surface in a single large step.

In a preferred X-ray tube in accordance with the invention the electrostatic lens electrode system comprises a first cylindrical electrode of rela-

2

tively small diameter co-axially surrounding the cathode and having an apertured diaphragm substantially in the plane of the effective emissive area of said cathode, an extension cylindrical electrode of relatively small diameter co-axial with and on the anti-cathode side of said first cylindrical electrode and a third cylindrical electrode of relatively large diameter co-axial with the two other cylindrical electrodes and extending at least over the whole length of the discharge path from cathode to anti-cathode.

The first and extension cylindrical electrodes may be and preferably are mechanically united so that the latter is also mechanically an extension of the former.

Means external of the tube, may be provided for adjusting along the axis of the tube the longitudinal position of the cathode in the tube. Instead of, or as well as, thus providing mechanical adjustment, the third cylindrical electrode may be provided (for electrical adjustment purposes) with an internal annular transverse partition which is positioned in a plane adjacent the plane of the anti-cathode end of the extension cylindrical electrode and has an aperture the diameter of which is approximately equal to that of said end.

The invention is illustrated in and further explained in connection with the accompanying drawings in which Figure 1 is an elevation partly in center line section of a preferred embodiment of the invention, with parts of the tube unnecessary to an understanding of the invention broken away and omitted to simplify the drawing; Fig. 2 is a conventional representation showing the run of equi-potential surfaces in a tube as illustrated by Fig. 1; and Fig. 3 shows a detail modification.

Referring to Fig. 1 the X-ray tube therein shown is of the customary elongated cylindrical shape the axis of which is indicated by the chain line X—X. In order that there may be an appreciation of the actual dimensions of the tube of Fig. 1 a scale of centimetres is included, though it is to be understood that the dimensions shown are only by way of example. The envelope of the tube has metal parts 1 and 2 mechanically joined and insulated from one another by a suitable glass part 3. The metal part 1 has a side or branch pipe 4 which leads to a vacuum pump (not shown) which is kept running when the tube is in use. It is to be understood, however, that the invention is equally applicable to tubes having permanently sealed envelopes as well as to tubes, such as that shown,

3

of the continuously pumped type. Mounted from one end of the envelope is a cathode shown as of the hairpin filament type. The filament, which is indicated at 5 is carried in any convenient way from a cylindrical mounting member 6 which houses the filament supports (not shown) and through which the filament heating leads (not shown) pass. In use the mounting member is in the region of cathode potential. Also carried from the mounting member is a first cylindrical electrode 7 of relatively small diameter which is also in the region of cathode potential and concentrically surrounds the cathode 5. By the expression "in the region of cathode potential" as employed in this specification is meant at cathode potential or different from cathode potential by an amount which is small in relation to the difference of potential between cathode and anti-cathode. Thus, to quote practical figures, in a tube in which the difference of potential between cathode and anti-cathode may be of the order of from 10 kv. to 50 kv. the cylindrical electrode 7 may be at earth potential and the cathode 5 itself may be given a positive bias up to, say, a couple of hundred volts or so. The electrode 7 has a diaphragm 8 with a central aperture 9 and is substantially co-planar with the cathode tip i. e. the effective emissive point thereof. The electrode 7 is extended to provide an extension cylindrical electrode 10 of the same diameter and also in the region of potential, this extension electrode terminating in an anti-corona ring 11 as well known per se. The electrode 10 need not be mechanically united with the electrode 7 though it is preferred to make it so. The electrode 7 is shown broken away to permit the hairpin filament 5 to be seen but the details of the filament leads and supports, being of any form well known per se, are not shown so as to simplify the figure.

To allow of longitudinal adjustment of the cathode the cathode structure is provided with a rearwardly extending axial stem 12 which passes through a bellows 13 and screws into a member 14 having a screwed stem 15 which extends through the rear end of the envelope. The stem 15 is engaged by an internally threaded gland member 16 which can be rotated by a knurled or winged member 17. The structure here is only diagrammatically shown but it will be obvious that by rotating the member 17 the cathode can be adjusted longitudinally back or forth along the axis.

Carried in the other metal end member 2 of the envelope is a tubular anti-cathode 18 which is illustrated as of the water cooled type having inlet and outlet pipes 19 for the cooling liquid. The anti-cathode is fixed in place by a tapered plug fixture 20 of normal type. Reference character 21 designates the normal X-ray tube window (shown dotted) and 22 designates the conventional guard and anti-corona rings.

In use, the electrodes 7 and 10 are maintained in the region of cathode potential as also is the metal part 1 of the envelope. The parts 7, 10 and 1 together constitute the preferably earthed members of an electrostatic lens system, the envelope part 1 also serving as an electrode which extends over and well beyond the whole electron discharge path from cathode to anti-cathode. The last mentioned electrode is, of course, maintained at a suitable positive potential with respect to the other electrodes 1, 7 and 10 which may be permanently connected together if desired by being structurally united as in the illus-

4

trated tube of Fig. 1. If desired, however, separate leads may be provided to the electrodes 1, 7 and 10 to enable the potentials applied thereto to be adjusted. In practice, however, these electrodes, if not all at exactly cathode potential, are as already explained, in the region of cathode potential and co-operate to provide an equi-potential surface, in the region of cathode potential, which surrounds the electron discharge and is of small diameter near the cathode, enlarging to a much bigger diameter beyond the anti-cathode end of the extension electrode 10. In general the potential of the parts 7, 10 and 1 will be earthed and the anti-cathode potential will be positive to earth but obviously, it is only relative potentials which matter and the anti-cathode might be earthed and the other electrodes held negative to earth.

Fig. 2 is an enlarged diagram showing the form of equi-potential line distribution obtained with this electrostatic lens system. Fig. 2 is a dia-grammatic section showing the essential electrodes on one side only of the axis of symmetry X-X. The references used in Figs. 1 and 2 refer to the same parts. Equipotential surfaces are indicated by thin curved lines marked with relative potentials in arbitrary units and the spacing between the filament (not shown in Fig. 2) and the anti-cathode is also subdivided into arbitrary units of division.

The following ranges of relative dimensions for the arrangement of Fig. 1 are given as a guide to construction: If the diameter of the electrode 7 and of the extension 10 is taken as unity, the axial length of the said extension 10, measured from the diaphragm 8 should be 0.75 ± 0.25 ; the axial spacing between the diaphragm 8 and the flat face of the anti-cathode should be 1.65 ± 0.25 ; the internal diameter of the envelope electrode 1 should be not less than 1.5 and preferably about 2; and the diameter of the tubular anti-cathode should be about 0.8.

Fig. 3 shows a detail modification differing from Fig. 1 in that the envelope electrode 1 is provided with a transverse partition electrode member 23 in a plane parallel to and adjacent the plane which passes through the far end of the extension electrode 10, said partition member having an axial aperture of about the same diameter as that of the electrode 10. Also, as illustrated in Fig. 3, an anti-corona ring 11a on the inner edge of the member 23 replaces the ring 11 of Fig. 1. The advantage of the arrangement of Fig. 3 is that it provides electrical adjustment of the lens to correct focus. This adjustment, which is obtained by varying the potential between the electrodes 1, 10 on the one hand and 1, 23 on the other is, from the point of view of simplification of structure, obviously advantageous as compared to providing for mechanical movement of the cathode as in Fig. 2, though both types of adjustment may be provided if desired. In Fig. 3 provision of electrical adjustment is indicated by showing separate leads 24, 25 taken to different points, one (or both) variable, on a potentiometer 26 which is connected across a source of potential (not shown). Of course, in any construction in accordance with this invention, the applied potentials must be selected, in accordance with known electron-optical principles, to suit the tube dimensions and produce the desired fine focus on the face of the anti-cathode but the provision of electrical adjustment as in Fig. 3, in conjunction with or instead of the mechanical adjustment provided by axial

movement of the cathode, gives great practical convenience without material added complications.

We claim:

1. A fine focus X-ray tube comprising an envelope, a cathode, an anti-cathode, an electrostatic focussing lens system, said lens system including a first cylindrical electrode of relatively small diameter co-axially surrounding said cathode and having an apertured diaphragm substantially in the plane of the effective emissive area of said cathode, an extension cylindrical electrode of relatively small diameter co-axial with and conductively connected with said first cylindrical electrode on the anti-cathode side thereof, and a third cylindrical electrode of relatively large diameter co-axial with the two other cylindrical electrodes and extending at least over the whole length of the discharge path from cathode to anti-cathode means, operable externally of said envelope for adjusting the position of said cathode and said electrostatic lens system as a unit longitudinally along the axis of said envelope, and means for applying a potential of the order of kilovolts between the cathode and anti-cathode and a potential not exceeding the order of tens of volts between the cathode and the electrostatic lens system.

2. A fine focus X-ray tube comprising an envelope, a cathode, an anti-cathode, an electrostatic focussing lens system, said lens system including a first cylindrical electrode of relatively small diameter co-axially surrounding said cathode and having an apertured diaphragm substantially in the plane of the effective emissive area of said cathode, an extension cylindrical electrode of relatively small diameter co-axial with and conductively connected with said first cylindrical electrode on the anti-cathode side thereof, and a third cylindrical electrode of relatively large diameter co-axial with the two other cylindrical electrodes and extending at least over the whole length of the discharge path from cathode to anti-cathode, said third cylindrical electrode forming part of said envelope means, operable externally of said envelope for adjusting the position of said cathode and said electrostatic lens system as a unit longitudinally along the axis of said envelope, and means for applying a potential of the order of kilovolts between the cathode and anti-cathode and a potential not exceeding the order of tens of volts between the cathode and the electrostatic lens system.

3. A fine focus X-ray tube comprising an envelope, a cathode, an anti-cathode, an electrostatic focussing lens system, said lens system including a first cylindrical electrode of relatively small diameter co-axially surrounding said cathode and having an apertured diaphragm substantially in the plane of the effective emissive area of said cathode, an extension cylindrical electrode of relatively small diameter co-axial with and on the anti-cathode side of said first cylindrical electrode, and mechanically united therewith and forming a continuous electrically conductive surface, and a third cylindrical electrode of relatively large diameter co-axial with the two other cylindrical electrodes and extending at least over the whole length of the discharge path from cathode to anti-cathode means operable externally of said envelope for adjusting the position of said cathode longitudinally along the axis of said envelope, and means for applying a potential of the order of kilovolts between the cathode and anti-cathode and a potential not exceeding

the order of tens of volts between the cathode and the electrostatic lens system.

4. A fine focus X-ray tube comprising an envelope, a cathode, an anti-cathode, an electrostatic focussing lens system, said lens system including a first cylindrical electrode of relatively small diameter co-axially surrounding said cathode and having an apertured diaphragm substantially in the plane of the effective emissive area of said cathode, an extension cylindrical electrode of relatively small diameter co-axial with and conductively connected with said first cylindrical electrode on the anti-cathode side thereof, and a third cylindrical electrode of relatively large diameter co-axial with the two other cylindrical electrodes and extending at least over the whole length of the discharge path from cathode to anti-cathode means operable externally of said envelope for adjusting the position of said cathode longitudinally along the axis of said envelope, and means for applying a potential of the order of kilovolts between the cathode and anti-cathode and a potential not exceeding the order of tens of volts between the cathode and the electrostatic lens system.

5. A fine focus X-ray tube comprising an envelope, a cathode, an anti-cathode, an electrostatic focussing lens system, said lens system including a first cylindrical electrode of relatively small diameter co-axially surrounding said cathode and having an apertured diaphragm substantially in the plane of the effective emissive area of said cathode, an extensive cylindrical electrode of relatively small diameter co-axial with and conductively connected with said first cylindrical electrode on the anti-cathode side thereof and mechanically united therewith and forming a continuous electrically conductive surface, and a third cylindrical electrode of relatively large diameter co-axial with the two other cylindrical electrodes and extending at least over the whole length of the discharge path from cathode to anti-cathode, said third cylindrical electrode being provided with an internal annular transverse partition which is positioned in a plane adjacent the plane of the anti-cathode end of the extension cylindrical electrode and has an aperture the diameter of which is approximately equal to the diameter of the anti-cathode end of the extension cylindrical electrode means operable externally of said envelope for adjusting the position of said cathode longitudinally along the axis of said envelope, and means for applying a potential of the order of kilovolts between the cathode and anti-cathode and a potential not exceeding the order of tens of volts between the cathode and the electrostatic lens system.

6. A fine focus X-ray tube comprising an envelope, a cathode, an anti-cathode, an electrostatic focussing lens system, said lens system including a first cylindrical electrode of relatively small diameter co-axially surrounding said cathode and having an apertured diaphragm substantially in the plane of the effective emissive area of said cathode, an extension cylindrical electrode of relatively small diameter co-axial with and on the anti-cathode side of said first cylindrical electrode, and mechanically united therewith and forming a continuous electrically conductive surface, and a third cylindrical electrode of relatively large diameter co-axial with the two other cylindrical electrodes and extending at least over the whole length of the discharge path from cathode to anti-cathode, said third cylindrical electrode forming part of said envelope and being

provided with an internal annular transverse partition which is positioned in a plane adjacent the plane of the anti-cathode end of the extension cylindrical electrode and has an aperture the diameter of which is approximately equal to the diameter of the anti-cathode end of the extension cylindrical electrode, and a corona ring carried by said partition on the side opposite the last mentioned end of said extension cylindrical electrode means operable externally of said envelope for adjusting the position of said cathode longitudinally along the axis of said envelope, and means for applying a potential of the order of kilovolts between the cathode and anti-cathode and a potential not exceeding the order of tens of volts between the cathode and the electrostatic lens system.
